UNITED STATES PATENT OFFICE.

HARRY TRASK, OF BROOKLYN, AND WILLIAM N. CARMICHAEL, OF NEW YORK, N. Y.

HEATING APPARATUS FOR FIRE-ENGINES.

SPECIFICATION forming part of Letters Patent No. 395,093, dated December 25, 1888.

Application filed June 11, 1888. Serial No. 276,669. (No model.)

To all whom it may concern:

Be it known that we, HARRY TRASK, residing in the city of Brooklyn, county of Kings, and State of New York, and WILLIAM N.

5 CARMICHAEL, of the city, county, and State of New York, have invented certain new and useful Improvements in Heating Apparatus for Fire-Engines, of which the following is a specification, reference being had to the accompanying drawings.

Our invention relates specially to the economical use and manipulation of steam as a means for heating, boiling, and raising to a steam-pressure the water contained within 15 the boiler of a fire-engine and its connections while at rest in the engine-house preparatory to a hasty exit of such engine at the breaking out of a fire.

It consists in the construction, arrangement, and combination of the several parts or portions comprising the apparatus, as hereinafter described and specified.

In the accompanying drawings, Figure 1 represents a side elevation of a plant embodying our improvements. Fig. 2 represents a partial view of the same, and Fig. 3 represents a special detail of improved slip-joint connection between the heating apparatus and the engine. In Fig. 1 the engine is represented in place and at rest with the boiler connected to the heating apparatus. In Fig. 2 the engine is disconnected and removed and the circulation-pipes shown dropped within the flooring out of the way and circulation-connections closed.

35 Similar letters of reference designate like parts or portions in all the figures.

The letter A designates a main steam-supply pipe connecting with a neighboring boiler 40 or with a street-supply system, such supply being preferably of high temperatures and pressures.

B designates a pressure-regulator, whereby the higher pressures supplied are reduced to 45 the required pressure for steaming, the temperature being kept at as high a degree as possible. This regulator is located in the pipe-connection between steam-supply pipe and the heating apparatus.

50 C designates a coil or pipe system, to which the steam from the supply is passed from the

pressure-regulator for effecting the heating and general circulation of the water through the heating apparatus and fire-engine boiler.

D designates a closed tank or chamber surrounding the coil or pipe system C. 55

C' designates an ordinary trap, to which the drip of the heater-coil passes.

E and E' designate the circulation inlet and outlet pipes and valves of chamber D. 60

F and F' designate hinge branches connecting the inlet and outlet pipes E and E' with upright pipes G and G', passing up through the floor of the engine-house.

g and g' designate a pair of three-way 65 valves located within upright pipes G and G', by means of which the upper portions of said pipes are emptied upon the withdrawal of the fire-engine.

H and H' designate slip-joints connecting 70 the uprights G and G' with the horizontal branches I and I', directly attached to the fire-engine boiler. At the outer or slip-joint end of these connections I and I' check-valves K and K' are located for closing such connections immediately upon the withdrawal 75 of the fire-engine to prevent the blowing out of the boiler. Extra screw stop-valves, J and J', are fitted in these pipes I and I' to be ready in case the check-valves should not operate. 80 Both the pipes I and I' and uprights G and G' are shown out of line with each other, the better to display both inlet and outlet circulation-connections. In practice they would naturally be put in line with each other. 85

L designates the fire-engine boiler, within which the steam-pressure is required to be raised and kept up by the apparatus while the engine is housed.

M designates the main floor or apartment, 90 containing the engine while at rest.

M' designates the basement, cellar, or lower floor of the engine-house, containing the heating apparatus.

N N' are positive connections attached to 95 timber between engine-floor and basement, adapted to operate the levers of the two three-way valves g and g' to open or close the three-way passages for the purpose of forming a continued connection through uprights G and G' 100 or of closing said connection and effecting the emptying of the water left in uprights G

and G' after the withdrawal of the engine. These valves g and g' discharge to a sewer or drain through pipes g^2 .

A special operating-rod, O, is attached to levers P, connected to and operating valves E and E', and adapted to project up through the flooring between main and basement portions and to be raised and lowered from above the flooring, effecting the opening and closing of the valves. A special shore, Q, is set to support this rod O in a lifted position. The shore Q is held in its upright supporting position by a hook, R, attached to the fire-engine platform.

15 The detailed construction of the slip-joint H between engine-pipes I and uprights G is shown in detail, Fig. 3. The lever T, to which is attached the stem of the check-valve K, is fastened and swings at t on pipe I, and is fitted 20 with a hook, t' , and lifting eye or pin t^2 . The slip-joint H is fitted with a slotted boss, t^3 , provided with a wedge-incline, t^4 , also the male and female portions h^2 and h^3 . In making the connection of this slip-joint the fire-engine is moved backward, presenting the portion h^2 to enter the sleeve h^3 . The entrance of h^2 into h^3 enters the lever T into slot t^3 , and the final connection is made by the hooking of t' without the slot t^3 . The movement 25 of the lever into the slot t^3 carries the end of lever T up the wedge-incline t^4 , lifting the stem of valve K and opening it ready for work. As the hook portion t' exits from the slot t^3 it drops into place to hold the slip-joint 30 together.

35 In the general operation of this apparatus as a whole the live steam enters through or from supply-pipe A, and is passed through the reducing-valve B, reducing the steam-pressure 40 from its maximum in the supply-pipe to a pressure best suitable to the furnishing of heat sufficient to develop a pressure of some fifteen, twenty, or twenty-five pounds within the fire-engine boiler. With a high quality 45 and pressure of steam from the supply the pressure beyond the reducing-valve may be regulated to a pressure of fifteen to twenty pounds, and with ample heating-surface a pressure of twenty to twenty-five pounds can be easily kept up in the fire-engine boiler. As the water in tank or chamber D becomes 50 heated, it rises and passes through upper valve, E, hinge-connection F, upright G, slip-joint H, check-valve K, and pipe I to the fire-engine boiler, thence down again through pipe I', check-valve K', slip-joint H', upright G', hinge-connection F', and lower pipe and valve, E', back to the heater tank or chamber D.

55 Upon an alarm of fire lever T is raised and unhooked at t' and the engine is released. Upon moving out, the shore Q is pulled from under the rod O by hook R, when the whole falls within the pocket S below the level of flooring. The dropping of rod O closes both 60 valves E and E' by the movement of lever P on each after ordinary methods, the weight O' assisting in the downward movement of

rod O. The separating of the slip-joint H withdraws all support from pipes G and G', and they too settle down into the pocket S 70 beneath the floor-level, and the check-valve K, rod R, and lever T move away with the fire-engine. Thus is the floor left clear for the passage of anything else. The dropping of the pipes G and G' to the position below 75 the floor-level, as shown in Fig. 2, causes the opening of the valves g and g' to the drain-pipe g^2 through the pull brought to bear upon their levers by the connections N and N', hung from the floor-beams above. 80

Upon the return of the engine it is backed toward the slip-joints, pipes G and G' are lifted to the proper level to receive plug h^2 , the connections made, and lever T moved to a hooking at t' . The lifting of the pipes G 85 and G' effects the closing of the drain-outlet of valves g and g' and the opening of direct communication from the lower to the upper portion of uprights G and G'. With the closing of the slip-joint H rod O is lifted, opening valves E and E' and effecting the complete connection of the apparatus. With the lifting up of the rod O shore Q is set to hold it up, and hook-rod R is adjusted to keep the shore Q in place till the engine upon moving away pulls it from under.

The hinge portions are fitted to revolve at both ends and permit the lowering of uprights G and G', as shown in Fig. 2, such hinge portions being seen to point downward 100 in this figure, instead of upward, as in Fig. 1. If only low-pressure steam can be had, there is of course no necessity for the reducing-valve.

What we claim as new, and desire to secure 105 by Letters Patent, is—

1. In a heating apparatus for fire-engines, in combination with a water-heating chamber, a steam-supply pipe provided with a reducing-valve, inlet and outlet pipes connecting said heating-chamber with the boiler of the fire-engine, a pair of swing pipe-joints connecting the lower ends of the inlet and outlet pipes with the heating-chamber, and slip-joints connecting the upper ends of said inlet and outlet pipes with the fire-engine boiler, substantially as and for the purposes set forth.

2. In a heating apparatus for fire-engines, in combination with a water-heating chamber, inlet and outlet pipes connecting said heating-chamber with the boiler of the fire-engine, a pair of swing pipe-joints connecting the lower ends of the inlet and outlet pipes with the heating-chamber, slip-joints connecting the upper ends of said inlet and outlet pipes with the fire-engine, and a pair of valves attached to the boiler, each valve being provided with a lever mating and passing into a slot in a lug attached to said slip-joint, substantially as and for the purposes set forth.

3. In a heating apparatus for fire-engines, in combination with a water-heating cham-

ber, inlet and outlet pipes connecting said heating-chamber with the boiler of the fire-engine, a pair of swing pipe-joints connecting the lower ends of the inlet and outlet pipes with the heating-chamber, slip-joints connecting the upper ends of the inlet and outlet pipes with the fire-engine boiler, a pair of inlet and outlet valves attached to the heating-chamber, a drop-rod connecting 5 with and operating said inlet and outlet valves, a prop to support said drop-rod when lifted to open said valves, a pair of drain-valves located beneath the upper slip-joint 10

portion of inlet and outlet connections, a pair of operating-levers attached to said drain-valves, and suspension-rods attached to said levers, whereby, the fire-engine moving away, the connections are released and drop to a pocket in the floor and communication with the heater is closed, substantially 15 as set forth.
